UNITED STATES PATENT OFFICE.

JOHN JUNGERS, OF GRAFTON, WISCONSIN.

FIREPOT FOR RANGES.

1,337,604.

Specification of Letters Patent.

Patented Apr. 20, 1920.

Application filed January 18, 1917. Serial No. 142,976.

To all whom it may concern:

Be it known that I, JOHN JUNGERS, a citizen of the United States, and resident of Grafton, in the county of Ozaukee and State 5 of Wisconsin, have invented new and useful Improvements in Firepots for Ranges, of which the following is a description, reference being had to the accompanying drawings, which are a part of this specification.

10 This invention has for its object to provide a fire pot for ranges which will not necessitate a lining of fire brick requiring replacement from time to time and leaking more or less air through the division cracks 15 to interfere with the draft and check the fire and cool off the oven.

Another object of the invention is to produce an airtight fire pot of cast metal construction in a single piece, of oval shape in 20 plan, and adapted to be dropped into a rabbeted support, and capable of being changed end to end therein.

Another object of the invention is to provide a fire pot of this type with a means for 25 blocking off a portion thereof to reduce the capacity of the fire pot at times when the full capacity is not required, thus economizing in the consumption of fuel.

With the above and other objects in view 30 the invention consists in the fire pot for ranges as herein claimed and all equivalents.

Referring to the accompanying drawings, in which like characters of reference indicate the same parts in different views:

35 Figure 1 is a plan view of a fire pot constructed in accordance with this invention;

Fig. 2 is a transverse sectional view thereof;

Fig. 3 is a longitudinal sectional view 40 thereof with the blocking device in place;

Fig. 4 is a plan view showing the manner in which the blocking device seals a portion of the fire pot; and

Fig. 5 is a reduced perspective view of 45 such blocking device.

In these drawings 10 indicates the range proper, having the usual oven 11, with the fire box 12 at one end thereof and the flue space 13 extending over the top thereof between it and the range top 14.

A supporting plate 15 extends across the fire box 12 on the level of the top of the oven 11 and tightly closes the top of the fire box from the oven to the end of the range and 55 from the front to the rear of the range except for an oval shaped fire pot opening

therein. The edges of this fire pot opening are rabbeted to receive the outwardly extending surrounding flange 16 of a cast metal fire pot 17 formed in one piece. This 60 fire pot 17 is of the same substantially oval shape as the opening and is supported entirely from the plate 15 by the engagement of its upper edge therewith. It is thus suspended in place and is free to expand and 65 contract without opening up joints or cracks and therefore without disturbing the airtight partition formed by it and its support between the fire box and the flue. The flange of the fire pot 17, by resting on the 70 supporting plate 15 with surrounding play, forms a tight joint therewith which will soon become packed with soot and dust to make it impossible for air to enter the flue around the fire pot and to compel the air to pass through the fire bed within the fire pot. The lower edge of the fire pot is preferably serrated to form spaced fingers 18 coöperating with the grate bars 19 therebeneath as usual to permit free access of air to the fire bed and to facilitate the removal of ashes and clinkers.

By means of the fire pot of a single piece cast metal construction suspended at its upper edge there is no crack or seam to open up 85 whether the fire pot is hot or cold and therefore there is no check upon the draft but all air is compelled to pass through the fire bed. With such a fire pot suspended at its upper edge and entirely free otherwise, it is 90 capable of expanding and contracting under varying temperatures without warping or losing its original oval shape. The oval shape is given to the fire pot to permit it to expand and contract as an arch and to avoid 95 binding in its seat. Being of an integral casting suspended at its upper edge, it is surrounded by open space and does not require a fire brick lining. Fire pots with sectional fire brick lining are subject to frequent 100 repairs in replacing the fire brick as they burn out, but they are more particularly objectionable because of the cracks or seams between the sections of fire brick lining opening up and permitting air to enter the fire 105 pot above the bed of coals, and thus interfering with the draft and cooling off the oven.

The fire pot of this invention can be reversed end to end if desired, and this without requiring the services of a stove expert, 110 for the fire pot merely rests on the ledge of the supporting plate 15 and may be lifted

from place and returned without difficulty. This also permits of repairs being made by obtaining a new fire box from the manufacturer and slipping it in the place of the old one when it has become broken or is otherwise unsuitable for further use. This feature is of great importance with ranges in use in country districts where it is difficult and expensive to obtain the services of a stove expert for making repairs.

The curved side walls and the flat top of the fire pot of this invention make it possible to provide a blocking device having a tight fit therewith for effectively blocking off a part of the fire pot when it is not desired to use the fire pot to its full capacity. For this purpose the blocking device shown in Fig. 5 is used, consisting of a vertical partition plate 20 forming a part of the same casting with a horizontal top plate 21. The vertical plate has its edges curved to correspond with the curvature of the interior of the fire pot so as to just fit therewith when the device is in position and is then forced toward the end of the fire pot as would be the result of the pressure of coal thereagainst. The top plate rests flat upon the upper edge of the fire pot and is free to slide thereon to permit of the movement of the vertical plate 20 necessary to effect its tight fit. Thus the pressure of the coal against the vertical partition 20 and the weight of the blocking device together serve to make the blocking device tightly seal a portion of the fire pot and prevent the leakage of air therethrough while the fire is confined to the open portion of the fire pot with a resulting economy in fuel in the operation of the range at times when the full capacity of the fire pot is not required.

The invention is not confined to any particular form of stove and there is no intention to impose such a limitation by the use of the term "range" for the term "range" as herein employed is intended to cover cook stoves generally.

What I claim as new and desire to secure by Letters Patent is:

1. In a range, the combination, with an oven and a fire box at the end thereof, of a supporting plate resting on the oven and extending across the fire box and fitting

tightly the walls thereof and provided with an oval shaped opening, an oval shaped bottomless basket-like fire pot provided with an outwardly extending flange at its upper edge resting upon the supporting plate around the edges of the opening with play permitting expansion of the fire pot, said fire pot being changeable end for end within the opening of the supporting plate, a blocking device for the fire box comprising a vertical plate connected with a horizontal plate, the horizontal plate being slidably mounted on the upper edges of the fire pot to permit the vertical plate wedging itself between the converging side walls of the fire pot at either end thereof as the horizontal plate is moved endward of the fire pot.

2. In a range, the combination, with a fire box, of a supporting plate extending over the fire box and having an oval shaped opening, an oval shaped bottomless basket-like fire pot having an outwardly extending flange at its upper edge resting upon the supporting plate adjacent the opening and being reversible end for end therein, a blocking device adapted to coöperate with either end of the fire pot having a top section slideable upon the upper edge of the fire pot and a vertical section movable into contact with the converging side walls of the fire pot at either end on endward movement of the top section.

3. The combination of a fire pot having side walls converging toward the end, a blocking device having an imperforate top portion slideable upon the upper edge of the fire pot and an imperforate vertical portion integral with said top portion and movable into close fitting contact with the converging walls of the fire pot on endward movement of the top portion, said blocking device coöperating with the side walls and upper edge of the fire pot to prevent passage of air through that portion of the fire pot covered by said device.

In testimony whereof, I affix my signature, in presence of two witnesses.

JOHN JUNGERS.
